ELECTROSTATIC COATING APPARATUS

Edwin M. Ransburg, Indianapolis, Ind., assignor, by mesne assignments, to Ransburg Electro-Coating Corp., Indianapolis, Ind., a corporation of Indiana

Original application March 16, 1946, Serial No. 654,830. Divided and this application November 18, 1950, Serial No. 196,374

3 Claims. (Cl. 118—51)

1

This application is a division of my application Serial No. 654,830, filed March 16, 1946, which is now abandoned.

This invention relates to the coating of articles in an electrostatic field and more particularly to a means for supporting and maintaining the article as a terminal of the electrostatic field during the coating process.

In electrostatic coating apparatus in which the article to be coated is supported on a grounded conveyor and is moved past a high potential electrode while liquid coating material is sprayed into the zone surrounding the article, it is desirable that a good electrical contact between the article and conveyor be maintained. As any given support for articles is repeatedly returned to the electrostatic coating field, it accumulates over a period of time a considerable coating of paint, which may prevent proper electrical contact of subsequent articles therewith. Also when the support passes through the coating zone without any item hung thereon, the contacting portion thereof may become coated. This prevents proper electrical contact between the article and conveyor which not only interferes with proper coating, but also may allow the article to accumulate a capacity charge which may raise the potential of the article high enough above ground potential to cause a spark to the grounded conveyor, and create a fire hazard.

An object of this invention is to provide electrostatic coating apparatus for applying a liquid coating material to articles in which the articles are always maintained as one terminal of an electrostatic field.

Another object of this invention is to provide a support for an article in an electrostatic apparatus which insures that there is at all times during the coating process a positive electrical connection between the article and a terminal of an electric circuit.

Another object of this invention is to provide a support for an article in an electrostatic coating zone, which has a portion shielded to prevent deposition of coating material thereon.

Another object of the invention is to provide in an electrostatic coating apparatus a support for an article to be coated which resiliently maintains an electrical connection therewith.

Another object of the invention is to provide in an electrostatic coating apparatus a support for an article to be coated that is so shaped that the material accumulated on the contact portion thereof will be held to a minimum.

The present invention will be described in 55 even when the hook is not loaded with an article,

2

greater detail in connection with the accompanying drawings in which are illustrated a preferred embodiment of the invention by way of example, and in which:

5 Fig. 1 is an elevation of an electrostatic coating apparatus embodying an overhead conveyor, Fig. 2 is an elevation of the hook support shown in Fig. 1,

10 Fig. 3 is a cross sectional view taken on line III—III of Fig. 2, Fig. 4 is a perspective view of a further modification illustrating a modified form of conveyor,

Fig. 5 is a perspective view of a detail of Fig. 4, Fig. 6 illustrates a further modification in perspective, and

15 Fig. 7 is a perspective view of a detail of Figure 6.

20 Referring to Figure 1, a plurality of insulator posts 1, suitably support electrode frames 2 and 3 in any suitable arrangement. Each electrode frame carries a plurality of fine wires, for example, as illustrated in Figure 4 of the application of Harold P. Ransburg, Serial No. 589,719 for Method for Coating Articles, filed April 23, 1945, now Patent No. 2,567,781, dated September 11, 1951. The frames are secured together by bottom electrode portion 6. The electrode wires are maintained by any suitable means, such as high voltage source 5, at a high electrical potential of the order of one hundred thousand volts

25 and the conveyor chain is grounded as at 4.

30 I-beam 10 which provides a track for a trolley 11 and a bar 12 depending from the trolley is engaged by a conveyor chain 13 by which it is moved. An article support, indicated generally

35 at 14 depends from chain 13 and is preferably in the form of a V-shaped metal hook having on the inner surface a sharp edge 18 (Fig. 2) which has a radius on the order of less than about $\frac{1}{2}$ inch. The bail 19 secured to the article 21, is inserted into the hook 17 and rests on sharp edge 18 at 22 and 23 (Figs. 2 and 3).

40 A spray nozzle 24 of any suitable type is supported to introduce into the electrostatic field between the article and electrodes, a stream of finely divided material, such as a settable finishing fluid, preferably accompanied by a carrier air stream, which is electrostatically deposited upon the surface of the article 21 and the bail 19. By

45 reason of the sharp edges of the hook 18 engaging the bail at 22 and 23, a good electrical connection therewith to ground is established. The sharp edge 18 remains relatively free of paint even when the hook is not loaded with an article,

due to the ionizing action of the sharp edge in the electrostatic field and the tendency of the liquid coating material to draw away from the edge.

In the modification illustrated in Figures 4 and 5, the overhead conveyor illustrated in Figure 1 is replaced by the conveyor 10 having spindles 11 extending upwardly therefrom, each spindle carrying a pulley 12 which is rotated by a traveling belt 13 or the like. The spindle 11 at its upper end carries a member of any suitable shape, shown as a metal plate 14 having cut out portions 15 and 16 which are crimped outwardly to form spring fingers 17 and 18. The object illustrated to be coated is a jar cap 11 having a threaded flange 12 and a cap liner 13 of insulation material which prevents the top of plate 14 from contacting the top of cap 11. However, when the cap is placed over the plate 14, the fingers 17 and 18 resiliently engage the threaded flange 12 on the interior and make electrical contact therewith. The resiliency of the fingers enables the cap to be easily removed from the support.

In the modification illustrated in Figures 6 and 7 the spindle 11 carries at its upper end a plate 16 having located about its edge a plurality of positioning pins 17. At the center of the plate there is suitably secured, as by soldering thereto, a spiral spring 18, the end of which may be pointed as indicated at 19. The object illustrated is a cake cover 11 to be coated on the exterior surface and remain uncoated on the interior. The cake cover 11 is placed upon the plate 16 and is more or less centered by the pins 17 on the interior thereof, while the spring 18 makes electrical contact with the cake cover. The disc portion 16 closes up the interior of the cake cover and prevents the entrance of coating material thereto. The spring 18 is pointed at 19 to present to the field an ionizing point which produces a corona discharge when not covered by an article. In this manner the point 19 which is the contact portion of the support will remain substantially free of coating material and insure good electrical contact between the support and the article to be coated.

The invention may be embodied in various other forms without departing from the spirit or scope thereof.

I claim:

1. In apparatus including a voltage source for electrostatically coating an electrically conducting article by exposing it to a spray of charged particles in a coating zone, the combination of a rigid support, a plurality of article-engaging portions carried by said support, resilient means acting between two of said portions and urging them apart when both engage the article, said article-engaging portions including one which is rigid and rigid with the support to locate the article relative to the support; one of the two portions between which said resilient means acts being electrically conductive and connected to said voltage source to maintain the article at an electrical potential substantially different from that of the charged particles.

2. The invention set forth in claim 1 with the addition that said rigid portion is a member adapted for reception in a hollow article, the two first mentioned portions being the free ends of resilient fingers mounted on opposite sides of said rigid portion.

3. In apparatus including a voltage source for electrostatically coating an electrically conducting article by exposing it to a spray of charged particles in a coating zone, the combination of a rigid support having a rigid portion adapted to support an article from below, a resilient member carried by said support and having a free end engageable with an article so supported and movable downwardly by the weight of the article, rigid abutment means on said support engageable with the article to locate it relative to the support, said resilient means being electrically conductive and connected to said voltage source to maintain the article at an electrical potential substantially different from that of the charged particles.

EDWIN M. RANSBURG.
